A. J. LOEPSINGER.
SPRINKLER HEAD.
FILED MAR. 11. 1918.

Inventor:
Albert J. Loepsinger
By James D. Johnston
Attorney:

UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF NEW YORK, N. Y., A CORPORATION OF NEW YORK.

SPRINKLER HEAD.

Application filed March 11, 1918. Serial No. 221,850.

To all whom it may concern:

Be it known that I, ALBERT J. LOEPSINGER, of the city and county of Providence, and State of Rhode Island, have invented certain new and useful Improvements in Sprinkler Heads; and I do hereby declare the following specification, taken in connection with the accompanying drawings, forming a part of the same, to be a full, clear, and exact description thereof.

The invention relates to improvements in sprinkler-heads and is designed primarily for use in connection with that class of sprinkler-heads known in the art as open sprinklers which are designed and adapted for use upon the exterior of buildings to direct a stream of water against the exterior wall of the building and through or against the windows thereof.

In sprinkler-heads of this character as heretofore produced, a deflector has been employed which has a flat surface arranged opposite the outlet opening and at right angles to the axis thereof. The great objection to the use of a deflector of this character resides in the fact that the stream of water issuing from the outlet opening is not only broken up after it issues from the nozzle and when it strikes the surface of the deflector which is arranged at right angles to the axis of the outlet opening, but the velocity and energy of said stream at the same time is greatly reduced, which in turn reduces the area of distribution.

The principal object of the present invention is to overcome the above objections and to provide a sprinkler-head of this type with a deflector of such a character as not to decrease the velocity of the stream of water to as great an extent as would a flat deflector, and also produce a wider and better distribution of said stream against the wall of the building protected.

More specifically the object of the invention consists in providing a sprinkler with a deflector of the above character which is arranged and adapted to direct the flow of water therefrom in different directions and in different volumes in each direction.

To these ends the invention consists in the novel construction and arrangement of parts hereinafter described and more particularly set forth in the claims, and relates to a species of the generic invention set forth

and claimed in my pending application filed July 20, 1921, Serial Number 486058, which originally was disclosed and claimed in this present specification.

In describing the invention in detail reference will be had to the accompanying drawings in which,

Fig. 1 is a front elevation of a sprinkler head embodying the present invention.

Fig. 2 is a vertical sectional view thereof.

Fig. 3 is an illustrative view showing the application of the sprinkler-head in use upon the side of the building in such manner as to throw a portion of the stream of water against the cornice of a building and the remainder of the stream against the wall or window of the building.

Referring to the drawings, 10 represents the frame of the sprinkler-head, 11 the tubular nozzle having external threads 12 for attachment to a water supply system and 13 the usual outlet opening. The frame 10 is inclined at an angle to the axis of the sprinkler nozzle, as shown in Fig. 2 and has secured thereto, or formed integral, a deflector 14 having upon its interior two laterally extending curved surfaces 15 and 16 and a raised rib 17 at the point of intersection of said curved surfaces. As shown the curved surface 15 is shorter than the curved surface 16, although they may be of any desired lengths. In consequence their degrees of curvature are different, and they deflect water to differing degrees from the axis of the nozzle. The utility of this in enabling the water to be directed as desired, against different shaped or positioned surfaces to be protected, is indicated in Fig. 3. By reason of the fact that the frame 10 is arranged at an angle to the axis of the sprinkler nozzle it will be seen that the raised rib 17 is in a plane outside of the axis of said nozzle and that the stream of water flowing from said nozzle will be divided at one side of its center so that a smaller portion of said stream will flow tangentially along the shorter curved surface 15 and a larger portion of said stream will flow tangentially along the longer curved surface 16.

It will be seen that the continuous curved surfaces upon the interior of the distributor will cause a gradual change in the direction of flow of the water in such a manner as not

to materially reduce the velocity, or energy thereof, and also result in the wider distribution of the stream.

Such a construction and arrangement of 5 deflector is desirable for use adjacent the roof of a building so that a small portion of the stream flowing from the sprinkler can be directed against the cornice of said building, while the greater portion of said 10 stream will be directed downwardly against the wall or window of the building as shown in Fig. 3.

With the above construction of deflector it will be seen that any desired plane of distribution 15 may be secured by varying the curvature of the curved surfaces and different planes of distribution may be secured in the same deflector.

It will be understood that I do not wish to 20 limit myself to the exact construction and arrangement of parts shown as it is obvious that various changes in details may be made without departing from the spirit and scope of the invention as set forth in the claims.

25 What I claim as my invention and desire to secure by Letters Patent is:

1. A sprinkler head comprising a nozzle and a deflector associated fixedly with it, said deflector having surfaces, along which separate parts of the water from the nozzle flow, rigidly supported in position with their initial portions approximately tangential to the stream from the nozzle, and jointly constituting a stream-dividing edge set across the 30 path of the stream at a location outside of the axis thereof, whereby the stream is divided into two unequal portions which are deflected diversely by said surfaces; said deflecting surfaces having terminal portions 35

which are extending at diverse angles with, 40 the axis of the nozzle at their respective terminations.

2. A sprinkler head comprising a nozzle and a deflector associated fixedly with it, said deflector having diverging deflecting surfaces, along which separate parts of the water from the nozzle flow, rigidly supported in position with their initial portions approximately tangential to the stream, one of 45 said deflecting surfaces being shorter than 50 and having less curvature than the other, whereby the stream is divided into portions, one for each said surface, which are deflected diversely by said surfaces.

3. A sprinkler head comprising a nozzle 55 and a deflector associated with it having surfaces along which separate parts of the water from the nozzle flow; said surfaces having initial portions approximately tangential to the flow and terminal portions separated from each other and delivering separated streams, whose stream guiding faces extend at diverse angles from the axis of the nozzle, thereby delivering the stream in sections at diverse angles from the axis. 60

4. A sprinkler head comprising a nozzle and a deflector having two deflecting surfaces arranged respectively to receive adjacent parts of the nozzle stream and by their deflection to flatten said parts into distinct 70 sheets; said deflecting surfaces terminating respectively at different angles from the axis of the nozzle.

ALBERT J. LOEPSINGER.
